UNITED STATES PATENT OFFICE.

JAMES M. THOMPSON AND OSCAR J. NEIGENFIND, OF ST. LOUIS, MISSOURI.

AEROPLANE.

Application filed July 16, 1924. Serial No. 726,367.

To all whom it may concern:

Be it known that we, JAMES M. THOMPSON and OSCAR J. NEIGENFIND, citizens of the United States, residing at St. Louis, in 5 the county of St. Louis City and State of Missouri, have invented new and useful Improvements in Aeroplanes, of which the following is a specification.

This invention relates to improvements 10 in aircrafts, the general object of the invention being to provide means whereby the craft can rise vertically and can hover in the air as well as move in a horizontal direction.

Another object of the invention is to provide a number of sets of planes with means 15 for moving each set in a circular path while each plane is revolving about its longitudinal axis so that the planes will exert an upward thrust on the downward movement 20 and will feather on the upward movement.

A further object of the invention is to provide means for tilting the planes longitudinally to cause the ship to move horizontally.

25 Another object of the invention is to provide automatic balancing means which include a weight.

This invention also consists in certain other features of construction and in the 30 combination and arrangement of the several parts, to be hereinafter fully described, illustrated in the accompanying drawings and specifically pointed out in the appended claim.

35 In describing the invention in detail, reference will be had to the accompanying drawings wherein like characters denote like or corresponding parts throughout the several views, and in which:—

40 Figure 1 is a plan view of the device.

Figure 2 is an end view thereof.

Figure 3 is a horizontal sectional view showing the driving means including the differential means.

45 Figure 4 is an enlarged detail sectional view showing the driving means for the planes or blades.

Figure 5 is a detail view showing the weighted balancing means.

50 Figure 6 is a section on line 6—6 of Figure 5.

Figure 7 is a sectional view through one of the blades or planes.

55 Figure 8 is a detail view of the central part of the frame 5 and showing a sleeve 8 therein.

In these views, 1 indicates the fuselage which is provided with upwardly extending parts 2 which have collars 3 at their upper ends through which a tubular shaft 4 passes. 60 A frame 5, composed of longitudinally extending truss members 6 and the front and rear transversely extending truss members 7 is arranged above the fuselage and connected with the same at the center by means 65 of the sleeves 8 which are carried by the truss members 5 and which fit over the tubular shaft 4. A bar 9 has a collar 10 at its inner end which fits over the tubular shaft 4 at the center thereof and this collar and 70 the sleeves 8 are fastened to the tubular shaft by means of the set screws 11. The outer end of the bar 9 has connected therewith a depending shaft 12 which has its lower part threaded and engages an internally threaded socket member 13 which is 75 connected with the fuselage so that when said shaft 12 is turned by the hand wheel 14 thereon it will lock the bar 9 by shortening the distance between the outer ends of the 80 bar 9 and the fuselage or increasing the distance, and the inner end of said bar is connected with the tubular shaft 4, so that said shaft will be caused to move with the bar and thus the frame 5 will be rocked on its 85 transverse center.

A shaft 15 is journaled at each side of the frame 5, the journals being connected with the ends of the members 7 and each shaft carries a pair of frames 16 which are 90 spaced apart and moved with the shaft. Thus the two shafts and their frames form a reel-like arrangement. A plurality of shafts 17 are rotatably mounted in each set of the frames 16 and a plane or blade 18 has its longitudinal central part connected with each shaft 17, the planes being arranged between the frames 16. These planes or blades are formed, as shown in Figure 7, and taper inwardly from their 95 outer edges to their centers. The drawings show each reel arrangement as being provided with four blades though it will of course be understood that any desired number of blades can be arranged in each set and as many sets used as desired. The frames 16 have bearing posts 19 on their outer faces for supporting the shafts 20, each shaft 20 being geared to a shaft 17 by the bevel gears 21 and the inner end of each shaft 20 is provided with a bevel gear 22. I prefer to arrange two of these shafts 20 110

on each of the frames 16. A bevel gear 23 is immovably connected with each arm of each member 7 and meshes with the gears 22 so that the shafts 20 will be rotated 5 through engagement of the gears 22 with the stationary gears 23 as the reel frame is rotated. The reel structures are rotated by means of the shafts 24 which are connected with the shafts 15 by the bevel gears 10 25, the shafts 24 being in alignment and having their inner ends passing into a housing 26 which encloses the differential means 27 to which the shafts 24 are connected. A drive shaft 28 is geared to the differential means within the housing and this shaft 28 is connected by the gears 29 with a shaft 30 which is supported in the frame and which is connected by the sprocket and chain arrangement 31 with a shaft 32 which 15 20 25 is journaled in the tubular shaft 4 and which is connected with a suitable power plant in the fuselage by the sprocket and chain arrangements 33. Brake drums 34 are placed on the shafts 24 and the brake 30 band 35 of each drum is connected to a stationary member 36 at one end and has its other end connected to the arm 37 of a T-shaped lever 38 which is pivoted to the frame at 39 and which has a weight 40 at the lower end of its stem.

The plane is provided with the usual vertically arranged rudder 41 for changing the horizontal course of the ship.

From the foregoing it will be seen that 35 the reel assemblies are revolved in opposite directions from the power plant of the fuselage by the means shown which include the differential means 27. As the reel assembly is revolved the blades are rotated about 40 their longitudinal centers and the parts are so arranged that the blades will offer the maximum amount of resistance to the air as they are descending and the minimum amount as they are rising so that the ship 45 will be lifted vertically by the planes. By tilting the frame 5 the angle of the blades will be changed so that they will act as propellers for driving the ship forwardly or rearwardly according to the direction of 50 tilt. If, for any reason, one set of planes should lift one side of the ship faster than

the other and cause the frame to tilt laterally, the lever 38 would be swung by its weight 40 and thus tighten the brake band 35 upon the drum and thus check 55 the movement of the assembly which is rotating too rapidly so that this brake arrangement works automatically.

This invention will permit the aircraft to rise in a vertical plane or at any angle desired and with it a ship can hover over a definite spot for an indefinite period. By tipping the frame carrying the blades the blades can propel the machine in a forward or backward direction and the differential means with the brake means will act to balance the device. By forming the blades or planes as shown in Figure 7 greater efficiency is secured and slippage is prevented. Revolving the two sets of blades 70 in a different direction serves to balance the device. By arranging the blades as shown a thrust from each plane is secured in the maximum portion of revolution and with the minimum amount of resistance. 75

It is thought from the foregoing description that the advantages and novel features of the invention will be readily apparent.

We desire it to be understood that we may make changes in the construction and 80 in the combination and arrangement of the several parts, provided that such changes fall within the scope of the appended claim.

What we claim is:—

An aircraft of the class described comprising a body, a frame tiltably mounted thereon, a reel device at each side of the device, differential means, a power plant connected with the same, a pair of shafts connecting the differential means with the 85 reel devices, brake means on the shaft, a weight operated member for applying the brakes when the ship tilts, blades carried by the reel devices, means for rotating the blades about their longitudinal centers as 90 the reels rotate and means for tilting the frame. 95

In testimony whereof we affix our signatures.

JAMES M. THOMPSON.
OSCAR J. NEIGENFIND.
